Primary Examiner — Paula Greene(74) *Attorney, Agent, or Firm* — Ohlandt, Greeley, Ruggiero & Perle(57) **CLAIM**

The ornamental design for the handle with joint, as shown and described.

DESCRIPTION

FIG. 1 is a first side perspective view of an exemplary embodiment a handle with joint according to the present disclosure illustrating a portion in phantom;

FIG. 2 is a second side perspective view of the handle with joint of FIG. 1;

FIG. 3 is a first side perspective view of the handle with joint of FIGS. 1 and 2;

FIG. 4 is a second side perspective view of the handle with joint of FIGS. 1 and 2;

FIG. 5 is a first side view of the handle with joint of FIG. 3;

FIG. 6 is a front view of the handle with joint of FIG. 3;

FIG. 7 is a second side view of the handle with joint of FIG. 3;

FIG. 8 is a rear view of the handle with joint of FIG. 3;

FIG. 9 is a top view of the handle with joint of FIG. 3; and,

FIG. 10 is a bottom view of the handle with joint of FIG. 3. The broken lines in the drawings illustrating environmental structure or boundaries that form no part of the claimed design.
